UNITED STATES PATENT OFFICE.

CARL MUEHLEISEN, OF BERLIN, GERMANY, ASSIGNOR TO MERGENTHALER LINOTYPE COMPANY, OF BROOKLYN, NEW YORK.

MEANS FOR TRANSFERRING THE MATRICES FROM THE FIRST ELEVATOR TO THE SECOND ELEVATOR OF A MATRIX-COMPOSING AND LINE-CASTING MACHINE.

Application filed March 15, 1927, Serial No. 175,450, and in Germany August 24, 1926.

In matrix composing and line casting machines such as those known commercially under the trade mark "Linotype", the composed line, as is known, is conveyed into a 5 first elevator by passing through a matrix delivery channel. After the casting operation, the first elevator raises the line of matrices and brings it to the front of a stop towards which the ribbed lifter bar of the 10 second elevator descends in order to receive the matrices from said first elevator, and convey them to the distributor, whilst leaving behind the justifying spacebands.

As the matrices, when the first elevator 15 is elevated, are slack as the result of the slackening of the spacebands, and the line therefore is loose, it may happen that thick matrices with ears located on one side, hang slantwise in the first elevator, and in such a 20 case the toothed combinations of those matrices are too low to engage the above named lifter bar when the matrices are moved from the first elevator toward said bar, and these matrices consequently will fall off.

25 The object of the present invention is to provide means by which the aforesaid difficulty is overcome. For this purpose, there is provided at the point at which the matrices are transferred from the first elevator 30 to the lifter bar, a spring-controlled stop hereinafter termed a resistant or yielding resistant, which is adapted to bear against the foot or preferably against one of the lower lugs of the foremost of the matrices in course 35 of transference to the lifter bar and thereby bring it to an upright condition and compel all the following matrices of the line to assume correspondingly upright positions. When the line is moved on to the lifter bar, 40 the resistant assumes a position which allows the matrices to be passed freely thereover.

The drawings illustrate by way of example three constructional forms of the invention and in these drawings:—

45 Figure 1 is a diagrammatic front elevation of the intermediate transfer channel with the lifter bar ready to receive a line of matrices from the first elevator then operatively registering therewith;

50 Figure 2 is a view similar to Figure 1 with the line shown as transferred to the lifter bar;

Figure 3 is a side elevation of Figure 2; Figure 4 represents two thick matrices in

the first elevator, one in incorrect position 55 and the other in correct position;

Figure 5 is a view corresponding to Figure 1 of a second constructional form;

Figure 6 is a view similar to Figure 5 with parts shown in different positions; 60

Figure 7 is a side elevation of Figure 6, and

Figure 8 is a front elevation of part of a third constructional form of the yielding resistant. 65

Like reference numerals are used to indicate like parts in all of the constructions shown.

The line of matrices 1, is assembled from the magazine, and is subsequently transferred to the first elevator all as already known in existing machines. After the line is cast, the first elevator 2, of which only a small fragment is shown in the drawings, moves upwardly with the said line, which, 70 immediately thereafter, is moved along the intermediate transfer channel 3 into which enters the lifter bar 4 of the second elevator. 75

When the first elevator 2 with the matrix line 1 reaches the position in which it is shown in Figure 1, that is to say, in which it registers with the channel 3 and lifter bar 4, the matrix line is moved rightward towards said bar 4 by a line shifter pusher similar to that identified by the numeral 5 in Figures 5 and 6. It may happen that the line contains thick matrices such as those shown in Figure 4 whose upper ears 6, by which they are suspended in the first elevator 2, are located at one side of the matrix whilst the toothed combinations 7 are located upon the opposite side. As the line is slack through the slackening of the spacebands, during the ascent of the first elevator 2, the thick matrices will be suspended at a slant as is that shown at the left of Figure 4, so that when the line is afterwards moved rightward, the combinations 7 are too low to engage with the teeth of the lifter bar 4. 90

According to the constructional form of the invention shown in Figures 1, 2, 3 and 4, a spring-controlled resistant 8 constructed of a thin leaf-spring is provided on the channel or channel casting 3 and adapted to bear against the foot or preferably against the lower lugs or, as illustrated in Figure 3, one of the lower lugs 9 of the foremost matrix of the line to be transferred from the first 95 100 105

elevator 2 to the lifter bar 4. The resistant 8 is attached to the upper arm of a lever 10 which is adapted to swing about a pivot 11 fast to the channel 3. In the position 5 shown in Figure 1 the resistant 8 rests against an abutment 12, and projects into the first elevator 2 and, as more particularly shown in Figure 4, brings into erect position any matrices which may be slantingly suspended in said elevator. If, when the 10 resistant 8 is in this position, the line of matrices 1 is pushed on to the lifter bar 4, all the matrices are brought to erect position so as to enable them to properly engage 15 with the lifter bar 4. The resistant 8 normally is held against the abutment 12 by a tension spring 13 which, in the manner shown in Figures 2 and 3, is connected to it and to the channel casting 3. During the 20 transference of the matrix line 1 to the lifter bar 4, the resistant 8 is moved against the action of the spring 13 by the advancing matrix line, the lever 9 as shown in Figure 2, being then rocked clockwise about the pivot 25 11. The nose of a spring detent 14 thereupon engages with a recess 15 in the lever 10 and yieldingly holds the latter locked, in such manner that the resistant 8 is prevented from contacting with the feet of the 30 matrices of the advancing line. The resistant 8 remains in this position until the whole matrix line has been transferred to the lifter bar 4 and, after the latter has been raised in the usual manner, the first elevator 35 2 again descends and when doing so, contacts with the lower arm of the lever 10 and causes the latter, together with the resistant 8, to turn anti-clockwise and return into the normal position in which said parts 40 are shown in Figure 1.

The abutment 12 is preferably so located that when the first elevator 2 is in its uppermost position, it forms an extension of the guide rail and serves to support the matrices 45 during their transfer to the lifter bar 4.

In the constructional form represented in Figures 5 to 7, the spring-controlled resistant and its lever are formed as a single entity identified by the numeral 16, which 50 is adapted to swing about the pivot 11. A spiral spring 17 (Figure 7) acting as a friction brake, encircles the pivot 11, and resiliently holds the resistant 16 in any position 55 to which it may be moved. The spring 17 is enclosed within a cap or cover 17a which is rigidly connected to the pivot stud 11 as by a pin or the like, and carries an arm 18 which serves to restore the resistant 16 into its operative position. For this purpose a pawl or so-called pusher 19 is pivoted to the usual line shifter link 20 attached to the line shifter lever 21. The said pusher 60 is yieldingly held in the position shown in the drawing by a spring 22. When the line shifter 5 is moved to the left, the pusher 19

will engage with the arm 18 and return it to the normal position in which it is shown in Figure 5.

When the first elevator 2 moves upwards, it will press against the arm 18 and thereby move it and the resistant 16 clockwise against the action of the spring 22, in order to leave the passage clear for the ascending matrix line 1. As soon, however, as the first elevator has passed the arm 18 and nears its uppermost position, the spring 22 comes into action and overcomes the brake action of the spring 17 on the resistant 16, and causes said resistant to return to its normal position, as in Figure 5, in which it will bear 80 against the foremost matrix of the line and bring into upright position any of the matrices which may be inclined in said line.

Finally, Figure 8 illustrates a constructional form in which the resistant is of the 85 character of a roller 23. In this construction the ascending first elevator 2, when it travels past the roller 23, presses the resistant a little way back, that is to say, rightward, and subsequently the resistant is restored into operative position by the action of a spring which, although not shown in the drawing, may be similar to that shown in Figures 1 to 3.

It is obvious that the constructional details of the foregoing arrangements may be varied without departing from the invention, for example, in place of the spring detent 14, a different type of detent may be employed for locking the resistant. The lever 10 and likewise the spring detent 14 are preferably so constructed that when in mutual engagement the resistant 8 will be held slightly away from the advancing line of matrices, so that the latter will not drag 105 over it.

Having described my invention, I declare that what I claim and desire to secure by Letters Patent is:—

1. The combination with means for transferring the matrices from the first elevator of a matrix composing and line casting machine to the distributor lifter bar, of a resistant located in the path of the foremost of the matrices to be transferred, said resistant by contact with said matrix serving to effect the erection of any matrices of the line which may hang slantwise prior to their transfer to the lifter bar.

2. The combination with means for transferring the matrices from the first elevator of a matrix composing and line casting machine to the distributor lifter bar, of a resistant located in the path of the foremost of the matrices to be transferred, said resistant by contact with said matrix serving to effect the erection of any matrices of the line which may hang slantwise prior to their transfer to the lifter bar and means supporting the resistant yieldingly in the path of the mat-

rices in course of transference so that said resistant is pushed by the advancing line of matrices out of the path of the latter.

3. The combination with means for transferring the matrices from the first elevator of a matrix composing and line casting machine to the distributor lifter bar, of a resistant located in the path of the foremost of the matrices to be transferred, said resistant by contact with said matrix serving to effect the erection of any matrices of the line which may hang slantwise prior to their transfer to the lifter bar, means supporting the resistant yieldingly in the path of the matrices in course of transference so that said resistant is pushed by the advancing line of matrices out of the path of the latter and an abutment in the path of the resistant for limiting its movement towards the first elevator.

4. The combination with means for transferring the matrices from the first elevator of a matrix composing and line casting machine to the distributor lifter bar, of a resistant located in the path of the foremost of the matrices to be transferred, said resistant by contact with said matrix serving to effect the erection of any matrices of the line which may hang slantwise prior to their transfer to the lifter bar, means supporting the resistant yieldingly in the path of the matrices in course of transference so that said resistant is pushed by the advancing line of matrices out of the path of the latter and a detent adapted to hold the resistant in its retracted position in order to prevent dragging of the line of matrices thereover, said detent being released by the first elevator during its return to casting position.

5. The combination with means for transferring the matrices from the first elevator of a matrix composing and line casting machine to the distributor lifter bar, of a resistant located in the path of the foremost of the matrices to be transferred, said resistant by contact with said matrix serving to effect the erection of any matrices of the line which may hang slantwise prior to their transfer to the lifter bar, means adapted to yieldingly retain the resistant in any of its operative positions, and means adapted to return the resistant into the path of the line of matrices.

6. The combination with means for transferring the matrices from the first elevator

of a matrix composing and line casting machine to the distributor lifter bar, of a resistant located in the path of the foremost of the matrices to be transferred, said resistant by contact with said matrix serving to effect the erection of any matrices of the line which may hang slantwise prior to their transfer to the lifter bar, means adapted to yieldingly retain the resistant in any of its operative positions, means adapted to return the resistant into the path of the line of matrices, and means in the path of the ascending first elevator, by contact with which the resistant is moved out of that path prior to its restoration to said path by the spring-controlled pusher.

7. The combination with means for transferring the matrices from the first elevator of a matrix composing and line casting machine to the distributor lifter bar, of a resistant located in the path of the foremost of the matrices to be transferred, said resistant by contact with said matrix serving to effect the erection of any matrices of the line which may hang slantwise prior to their transfer to the lifter bar and an abutment against which bears the resistant and which forms an extension of the guide rail for the matrices in the first elevator when the latter is in its highest position.

8. In apparatus such as described, the combination with a first elevator adapted to raise a line of matrices, and a lifter bar adapted to receive said line when it is moved endwise out of the raised elevator, of a resistant located in the path of the ascending matrices, which by contact with an obliquely hanging matrix of the line will bring said matrix into erect position.

9. In apparatus such as described, the combination with a first elevator adapted to raise a line of matrices, and a lifter bar adapted to receive said line when it is moved endwise out of the raised elevator, of a resistant located in the path of the ascending matrices, which by contact with an obliquely hanging matrix of the line will bring said matrix into erect position and a pivot for said resistant upon which it will turn by the matrix line when the latter is moved endwise out of the first elevator.

In testimony whereof I have affixed my signature hereto.

CARL MUEHLEISEN.
